[57] CLAIM

The ornamental design for a video conference camera screen, as shown and described.

DESCRIPTION

FIG. 1 is a front elevational view of the video conference camera screen showing my new design;

FIG. 2 is an enlarged front elevational view thereof;

FIG. 3 is a front elevational view of an alternate embodiment of FIG. 1; and,

FIG. 4 is an enlarged front elevational view of FIG. 3. The rear view of the video conference camera screen of the present design is the mirror-image of the front elevational view illustrated in FIG. 1.

The video conference cabinet is shown in broken lines for illustrative purposes only and forms no part of the claim.
